UNITED STATES PATENT OFFICE.

JOHN G. MARTIN, OF WATERBURY, CONNECTICUT.

DESIGN FOR A SPOTLIGHT.

Application filed January 9, 1926. Serial No. 16,019. Term of patent 7 years.

To all whom it may concern:

Be it known that I, JOHN G. MARTIN, a citizen of Greece, residing at Waterbury, in the county of New Haven and State of Connecticut, have invented a new, original, and ornamental Design for Spotlights, of which the following is a specification, reference being had to the accompanying drawing, forming part thereof.

In this drawing:

Fig. 1 is a side view of the spotlight.
Fig. 2 is a front view of the same.

I claim:

The ornamental design for a spotlight as shown.

JOHN G. MARTIN.
